UNITED STATES PATENT OFFICE.

MAURICE BLUMENTHAL, OF BROOKLYN, NEW YORK.

TOOL FOR DETACHING OBSTRUCTIONS FROM ELECTRIC-WIRE CONDUITS.

1,111,208.

Specification of Letters Patent. Patented Sept. 22, 1914.

Application filed January 14, 1914. Serial No. 811,988.

To all whom it may concern:

Be it known that I, MAURICE BLUMENTHAL, a citizen of the United States, and residing at Brooklyn, in the county of Kings 5 and State of New York, have invented certain new and useful Improvements in Tools for Detaching Obstructions from Electric-Wire Conduits, of which the following is a specification, such as will enable those 10 skilled in the art to which it appertains to make and use the same.

This invention relates to tools or instruments for detaching obstructions from the interior of electric wire conduits used for 15 telegraph, telephone and other purposes, and which are usually employed in connection with what are known as "jar rods" which are usually composed of detachably connected parts, so that the length thereof 20 may be increased or decreased as desired, said rods being adapted to be detachably connected with the tool or instrument; and the object thereof is to provide an improved tool or instrument of this class which is simple in construction and effective in operation, and particularly designed for use in conduits which are rectangular in cross section, and in either what are called single 25 or multiple conduits, a further object being 30 to provide a tool or instrument of the class specified with improved means for recovering such a tool or instrument, or removing it from a conduit, if at any time it should become detached from the handle or "jar 35 rod".

The invention is fully disclosed in the following specification of which the accompanying drawings form a part, in which the 40 separate parts of my improvement are designated by suitable reference characters in each of the views, and in which:—

Figure 1 is a plan view showing one form 45 of my improved tool or instrument;—Fig. 2 a sectional side view thereof;—Fig. 3 a cross section on the line 3—3 of Fig. 1;—Fig. 4 a cross section on the line 4—4 of Fig. 2;—Fig. 5 a view similar to Fig. 1, but showing a modification;—Fig. 6 a cross section on the line 6—6 of Fig. 5.

50 In the practice of my invention, I provide a tool of the class specified, comprising a body portion *a* which is oblong and box-shaped in cross section, or composed of a bottom *a*² and sides *a*³, and both ends of 55 which are open, as shown at *a*⁴ and *a*⁵. The

open end *a*⁵ is provided with a handle shank *b* which is rectangular in cross section and preferably square, as shown in Fig. 13, and as clearly indicated in Figs. 1 and 2, and the inner end of said shank is provided with, or 60 formed into a plate *b*² which is riveted to the bottom *a*² of the body of the tool, as shown at *c*, and the outer end of the shank *b* is provided with a circular head *b*³ having a threaded bore *b*⁴, and at *d*, I have shown 65 one part or section of a handle or "jar rod" provided with a screw threaded extension *d*² adapted to be screwed into the socket *b*⁴.

The end of the bottom *a*² of the end of the 70 tool, opposite the handle shank *b* is beveled downwardly to provide a cutting edge *a*⁶, and the corresponding ends of the sides *a*³ are also preferably provided with similar cutting edges *a*⁷, and this completes the 75 tool, as far as its use for the purpose of removing or loosening obstructions from the interior of conduits of the class specified are concerned, it being understood that in this operation, or in this use of the tool, the 80 said tool is manipulated or operated in the same manner as other devices of this class.

In order to provide means to recover a 85 tool of this class when lost in a conduit, or accidentally detached from the handle or "jar rod", in the operation thereof, I pivot in the top part of the open and cutting end of the tool, or the body thereof, as shown at *e*, a hanger *f* which is adapted to serve as a "pick up", and when a tool of this class is 90 lost in a conduit, or accidentally detached from the handle or "jar rod", in the operation thereof, another and similar tool is used as a recovery tool and is passed into the conduit in such manner that the head *b*³ 95 of the shank of the lost tool will pass into the open end of the recovery tool, in which operation, the hanger *f* is swung inwardly or backwardly by the head *b*³ of the shank of the lost tool, and in the outward movement or withdrawal of the recovery tool, the hanger *f* therein will catch against the head *b*³ of the lost tool, and the latter may be withdrawn from the conduit, as will be readily understood.

The construction shown in Figs. 5 and 6 is 100 the same as that shown in Figs. 1 to 4 inclusive, except, that in place of the hanger *f*, I secure to the inner side of one side of the body 105 of the tool, as shown at *g*, an inwardly and

backwardly directed spring *h* which will operate in the same manner as the hanger *f*, in the operation of recovering a tool of this class, when lost in a conduit, or detached 5 from the handle or "jar rod."

From the foregoing description, it will be seen that all the forms of tools shown are provided with shanks which are rectangular or square in cross section and provided with 10 circular heads having screw threaded sockets, and the object in providing shanks which are angular in cross section is to facilitate the connection of the handles or "jar rods" with the heads of said shanks, 15 in which operation the tool or tools, may be placed on a table or on the ground, and a spanner or similar device may be passed down over the shank or shanks, and the tool or tools held stationary, while the handles 20 or "jar rods" are being screwed into the heads of said shanks, and a reversal of this operation will detach the handles or "jar rods" when necessary.

It will also be seen that in all the forms 25 of construction the body of the tool is rectangular in cross section and in the construction shown in Figs. 1 to 6 inclusive, said body of the tool is rectangular and box-shaped in form and is open at both ends, 30 and these forms of construction facilitate the use of a tool of this class in a conduit which is angular in form in cross section, and the box-shaped form of the tool also facilitates the removal from the conduit of obstructions 35 of various kinds and classes after they have been detached from a wall or walls of the conduit by reason of the fact that said obstructions will collect or may be collected in

the body of the tool and withdrawn from the conduit with the tool. 40

Having fully described my invention, what I claim as new and desire to secure by Letters Patent:

1. A conduit cleaning tool of the class described comprising a body portion having a 45 jar-rod coupling at one end and the opposite end of which is provided with a cutting edge, and with a catch device adapted to engage the coupling of a similar tool lost in a conduit. 50

2. A conduit cleaning tool of the class described, comprising an oblong box-shaped body portion open at one end and provided with a cutting edge, the opposite end being provided with a jar rod coupling, and the 55 open end being also provided with a catch device adapted to engage the coupling of a similar tool lost in a conduit.

3. A conduit cleaning tool of the class described, comprising an oblong body portion 60 rectangular in cross section and box-shaped in form and open at one end and provided with a cutting edge, the opposite end of the tool being provided with a jar rod coupling head, the open end being also provided with 65 a pivoted catch device adapted to engage the coupling head of a similar tool lost in a conduit.

In testimony that I claim the foregoing as my invention I have signed my name in 70 presence of the subscribing witnesses this 9th day of January, 1914.

MAURICE BLUMENTHAL.
